PISTON ENGINE OR PISTON PUMP

Rudolf Schmidt, Vienna, Austria

Application January 6, 1931, Serial No. 506,926,
and in Austria January 15, 1930

9 Claims. (Cl. 103—150)

I have filed an application in Austria on January 15, 1930.

This invention relates to piston engines (piston pumps) having a casing, provided with an inlet valve and an outlet valve and a piston reciprocating within the said casing. The object of the invention is the arrangement of an annular elastic diaphragm of undulated sheet metal, clamped at its inner circumference to the outer wall of the piston and at its outer circumference to the inner wall of the casing.

One mode of carrying out the invention is illustrated by way of example on the accompanying sheet of drawing in which Figs. 1 and 2 are two vertical sectional views, the sections being taken at planes which are vertically disposed to each other. Fig. 3 is a detail view and Figs. 4a to 4g show some constructions of the diaphragm.

20 The piston 1 reciprocating in the casing 2, 5 of the engine forms a working chamber 3 which is provided with an inlet valve 3a and an outlet valve 3b. The piston is packed by a diaphragm 4 with respect to the parts 2 and 5 of the casing. A crank mechanism, comprising a piston rod 6, a springy connecting rod 7 provided at its end with the crank-pin bearing 8, serves for driving the reciprocating piston 1. 25 The flywheel 10 is fixed to the crank-shaft 9 and carries a rubber-ring 11, which co-operates as a friction wheel with a friction roller 12, mounted on the shaft of a driving motor 13, hinged at 14 to the casing, and pressed down by its weight or by suitable auxiliary weights G.

30 The common diaphragm pumps are adapted for very little pressures having very small strokes. According to the present invention diaphragms are used, which are adapted for great differences of pressures. For this purpose the annular diaphragm 4 is provided with ring shaped corrugations and is of such size that, in view of the deformation, corresponding to the piston-stroke, the bending stress does not amount to more but 35 also not to much less than the half of the stress to which the material is subjected. The deeper corrugations are forced from the clamping zones, where the greatest bending moments of pressure and deformation are present, towards the middle where no bending moment is present, because the radial stresses additionally subject to bending the base of the corrugations. The exact shape of the corrugations results from the fact that, in case of an even plate, the tension results at every point from a circumferential bending stress produced by the curvature of the

face and from a radial bending stress produced by deformation and pressure, and further by stretching of the base of the corrugations and inclining the latter. From these strains can be found by theory the shape of the corrugations 6 for the smallest tension and at the greatest bending of the lamination. Annular laminations constructed in this way allow comparatively long strokes from $\frac{1}{2}$ to 1 centimetre even in case of a very small width of the annulus (in a practical construction for instance 40 millimetres). 6

Figs. 4a-4g show various forms of the diaphragm.

The diaphragm illustrated by Fig. 4a is formed with ring shaped corrugations and with a wavy 7 line as cross section, with amplitudes, having the maximum M between the inner diameter d_i and the middle diameter d_m nearer to the latter and gradually decreasing to zero towards the inner diameter d_i and towards the outer diameter d_a of the diaphragm ring.

The diaphragm illustrated by Fig. 4b is formed with ring shaped corrugations and with a wavy 8 line as cross section, with amplitudes, having the maximum M between the inner and the middle diameter nearer to the latter and decreasing little or not towards the outer diameter.

The diagram illustrated by Fig. 4c is formed with ring shaped corrugations and with a wavy 8 line as cross section, with amplitudes, having the maximum in the middle diameter and gradually decreasing to zero towards the inner and towards the outer diameter of the diaphragm ring.

The diaphragm illustrated by Fig. 4d is formed with ring shaped corrugations and with a wavy 9 line as cross section, with amplitudes, having the maximum in the middle diameter and decreasing little or not towards the outer diameter but decreasing to zero towards the inner diameter.

A plurality of superposed diaphragms are employed if it is desired to further reduce the thickness of the several sheets and to increase the stroke. In case of compression, one diaphragm sheet rests on the other, so that the strain is distributed to all diaphragms. Either all diaphragms are fixed to the casing and piston and prevented from rubbing on one another by interposed lubricants, or only the first diaphragm is fully clamped in order to close the working chamber, while the other diaphragms are gradually shortened towards the zone of the greatest bending stress by reducing their outer diameter, similarly to the several plates of a plate-spring, used for instance as a vehicle-spring (Fig. 3).

In order to attain the greatest possible stroke 1

of the diaphragm at a given thickness of the sheet metal, according to Figs. 4e, 4f and 4g the diaphragm is formed with ring shaped corrugations and with a wavy line as cross section, the corrugations having a curved or wavy middle line and may be arranged symmetrically with respect to this middle line.

I claim—

1. In a pump comprising a casing having an inlet valve and an outlet valve and provided with a piston reciprocating within the casing, an annular elastic diaphragm clamped in a fluid tight manner at its inner circumference to the outer wall of the piston and at its outer circumference to the inner wall of the casing, the said diaphragm being formed with ring shaped corrugations and with a wavy line as cross section, with amplitudes, having the maximum between the inner and the middle diameter nearer to the latter and gradually decreasing to zero towards the inner and towards the outer diameter of the diaphragm ring.
2. In a pump comprising a casing having an inlet valve and an outlet valve and provided with a piston reciprocating within the casing, an annular elastic diaphragm clamped in a fluid tight manner at its inner circumference to the outer wall of the piston and at its outer circumference to the inner wall of the casing, the said diaphragm being formed with ring shaped corrugations and with a wavy line as cross section, with amplitudes having the maximum between the inner and the middle diameter nearer to the latter and decreasing little or not towards the outer diameter.
3. In a pump comprising a casing having an inlet valve and an outlet valve and provided with a piston reciprocating within the casing, an annular elastic diaphragm clamped in a fluid tight manner at its inner circumference to the outer wall of the piston and at its outer circumference to the inner wall of the casing, the said diaphragm being formed with ring shaped corrugations and with a wavy line as cross section, with amplitudes, having the maximum in the middle diameter and gradually decreasing to zero towards the inner and towards the outer diameter of the diaphragm ring.
4. In a pump comprising a casing having an inlet valve and an outlet valve and provided with a piston reciprocating within the casing, an annular elastic diaphragm clamped in a fluid tight manner at its inner circumference to the outer wall of the piston and at its outer circumference to the inner wall of the casing, said diaphragm being formed with ring shaped corrugations and with a wavy line as cross section with amplitudes, having the maximum in the middle diameter and decreasing little or not towards the

outer diameter but decreasing to zero towards the inner diameter.

5. In a pump comprising a casing having an inlet valve and an outlet valve and provided with a piston reciprocating within the casing, an annular elastic diaphragm clamped in a fluid tight manner at its inner circumference to the outer wall of the piston and at its outer circumference to the inner wall of the casing, the said diaphragm being formed with ring shaped corrugations and with a wavy line as cross section, the corrugations having a curved or wavy middle line.

6. In a pump comprising a casing having an inlet valve and an outlet valve and provided with a piston reciprocating within the casing, an annular elastic diaphragm clamped in a fluid tight manner at its inner circumference to the outer wall of the piston and at its outer circumference to the inner wall of the casing, the said diaphragm being formed with ring shaped corrugations and with a wavy line as cross section, the corrugations having a curved or wavy middle line and being arranged symmetrically with respect to this middle line.

7. In a pump comprising a casing having an inlet valve and an outlet valve and provided with a piston reciprocating within the casing, an annular elastic diaphragm clamped in a fluid tight manner at its inner circumference to the outer wall of the piston and at its outer circumference to the inner wall of the casing, the said diaphragm being formed with ring shaped corrugations, and with a wavy line as cross section, and composed of a plurality of superposed plates.

8. In a pump comprising a casing having an inlet valve and an outlet valve and provided with a piston reciprocating within the casing, an annular elastic diaphragm clamped in a fluid tight manner at its inner circumference to the outer wall of the piston and at its outer circumference to the inner wall of the casing, the said diaphragm being formed with ring shaped corrugations, and with a wavy line as cross section, and composed of a plurality of superposed plates, becoming gradually shorter in the manner of a plate spring.

9. In a pump comprising a casing having an inlet valve and an outlet valve and provided with a piston reciprocating within the casing, an annular elastic diaphragm clamped in a fluid tight manner at its inner circumference to the outer wall of the piston and at its outer circumference to the inner wall of the casing, the said diaphragm being formed with ring shaped corrugations, and with a wavy line as cross section, and composed of a plurality of superposed plates, grease or liquid lubricant being enclosed between the several plates of the diaphragm.
